(57) **CLAIM**

The ornamental design for terminal for a power tool, as
shown and described.

DESCRIPTION

FIG. 1 is a first perspective view of a terminal for a power
tool according to a first embodiment.

FIG. 2 is a second perspective view of the terminal for a
power tool of FIG. 1.

FIG. 3 is a third perspective view of the terminal for a power
tool of FIG. 1.

FIG. 4 is a front view of the terminal for a power tool of FIG.
1.

FIG. 5 is a first perspective view of a terminal for a power
tool according to a second embodiment.

(Continued)

FIG. 6 is a second perspective view of the terminal for a power tool of FIG. 5.

FIG. 7 is a third perspective view of the terminal for a power tool of FIG. 5; and,

FIG. 8 is a front view of the terminal for a power tool of FIG. 5.

The broken lines are included for the purpose of illustrating portions of the terminal for a power tool and form no part of the claimed design.
